UNITED STATES PATENT OFFICE.

GEORGE H. FORSYTH, OF CHICAGO, ILLINOIS, ASSIGNOR TO MOTOR WHEEL CORPORATION, OF LANSING, MICHIGAN, A CORPORATION OF MICHIGAN.

DISK WHEEL.

Application filed March 3, 1922. Serial No. 540,678.

To all whom it may concern:

Be it known that I, GEORGE H. FORSYTH, a citizen of the United States, residing at Chicago, in the county of Cook and State of Illinois, have invented certain new and useful Improvements in Disk Wheels, of which the following is a specification.

My invention has to do with disk wheels and has for its principal object the provision of a wheel of the disk type wherein a composite or non-metallic disk is rendered susceptible of employment instead of the usual sheet steel disk, without impairment of strength under dead load, resistance to deforming stresses in road use, and life and efficiency under weather conditions and attack of the elements; all accompanied by a reduced cost of production, the elimination of noises due to resonance and an enhanced adaptability both to heavy commercial and light pleasure cars. I accomplish this object by the employment of a disk having a substantially lower coefficient of elasticity than sheet steel, advantageously of non-metallic material and preferably of organic fibrous material in the form of laminated wood with the grain of the different layers disposed angularly, or pulp board, or a combination of such materials with or without a reinforcing inlay of steel interlocked with the other material; and I shape the disk and so assemble the same with the hub and rim as to place and maintain the disk under radially reacting stress, whereby to strengthen and reinforce the same against deformation by strains of use acting in the plane of the wheel or laterally thereof.

In order that the invention and its use may be readily understood by those skilled in the art I have set forth several embodiments of the same in the accompanying drawing and in the following detailed description predicated thereon. It will be understood that the principles of the invention are adaptable to other varied embodiments without sacrifice of their material advantages, wherefore the drawing and description are not to be taken in an unnecessarily limiting sense but as rather illustrative of the invention.

In the drawing, Figs. 1 to 7 inclusive represent in radial section fragmentary portions of disk wheels embodying the invention.

In Figs. 1, 2, 3 and 4 the disk is illustrated as comprising multiple sheets 11 of wood

forming a laminated disk with the grain of one sheet angularly disposed relative to the grain of the adjacent sheet. The sheets comprising the disk, whether two or more in number, are shown in these figures as 60 lying in contact throughout the extent of the disk.

In Fig. 5 the fibrous sheets forming the disk are assembled with a metallic reinforcing inlay 12, such as sheet steel, and 65 preferably secured thereto in any suitable manner, although they may be independent of each other and shaped in the process of forming so as to lie in intimate contact throughout their extent. 70

In Fig. 6 the disk is shown as comprising multiple sheets 13 of organic fiber such as wood pulp having imbedded therein an inlay sheet 14 of steel which is advantageously foraminous being provided at spaced 75 intervals with holes 15 by means of which the steel inlay and the fibrous sheets 13 are interlocked. It will be understood that there may be any desired number of successive layers of metallic and non-metallic 80 sheets constituting the disk.

Having reference to Fig. 7 the disk is shown as comprising sheets 16 which may be of non-metallic or metallic nature, but preferably of sheet steel. In this instance 85 the component sheets 16 are out of parallelism adjacent the wheel periphery and in its intermediate portion for a purpose which will be more clearly defined hereinafter.

It will be understood that the sheet materials employed as component parts of the disk, other than the inlays 12 of Fig. 5 and 14 of Fig. 6, have a decidedly lower coefficient of elasticity than has steel such as has been heretofore employed in the making of disk wheels, and such materials also possess in a less degree the property of resistance to deformation. I have found that while such materials are ordinarily not adapted to withstand the strains to which automobile wheels are subjected, yet when assembled with the hub and with the rim in such manner as to place and maintain the disk under decided stress acting radially, the elasticity and resistance of such materials is highly augmented and the wheel as a whole has a strength amply sufficient to meet all requirements in this relation. 100 105

In Figs. 1 and 7 the component sheets of the disk are forwardly arched at the hub 110

portion indicated by the reference numeral 17 and when assembled with the hub by means of the bolts 18 are flattened to a considerable degree whereby the force applied laterally by the bolts reacts radially of the disk and stresses the same against the constrictive force exerted by the peripheral portion of the disk.

In all of the figures of the drawing means of assembling the rim 19 with the peripheral portion of the disk acts through force laterally applied and re-acting inwardly in a direction toward the hub to stress not only the intermediate portion of the disk but also the peripheral portion 20 thereof. Whether this deforming force is applied at the hub or at the periphery or both, the disk throughout its area is subjected to and maintained under radial stress and its force of resistance to and recovery from strains is greatly enhanced. In Fig. 7 this stressing of the disk is further manifested in causing a wider separation of the sheets in their intermediate portion and, advantageously, the rear hub plate 21 and the backing plate 22, normally spaced from the rear sheet 16 serve as lateral abutments to the disk when sprung to the position shown in dotted lines at 16°.

As a means of assembling the disk with the rim and stressing the same by inward radial reaction various expedients may be employed as for instance:

In Fig. 1 an annular felly member 23 is shown as occupying a position to encompass and constrict the peripheral portion 20 of the disk, the two normally having an inclined relation to each other and being assembled by a wedging action exerted by the nut 24 and the head 25 of the bolts 26. To distribute the effect of the bolt head 25 and prevent rupture of the disk 11 a wide washer 27 is employed beneath the bolt head. The rim 19 is then assembled upon the felly 23 by means of the shim 28 which may be annular or divided into a number of individual shims and held adjustably in place by means of the nuts 29. The rim is interlocked with the felly by the usual driving lug 30. In this form of construction also the disk is shown as anchored to the hub plate 21 by bolts 31 having cooperating washers 27 bearing upon the concave face of the disk.

In Fig. 2 a similar felly member 23 is employed, the section being taken at the valve stem rather than at the driving lug. The peripheral portion 20 of the disk is slotted as shown at 20° and the felly member is also slotted as indicated at 23°, to enable the rim with its associated tire and valve stem 32 to be withdrawn by a horizontal movement to the front through the slots 20° and 23°.

As shown in Fig. 3 the peripheral por-

tion of the disk is not deflected to the rear but the felly member 33 overlies the margin of the disk and the rim 19 is assembled therewith by a wedging action exerted by the bolts 34, resulting in the stressing of the wheel.

In Fig. 4 the felly member 35 has a relation to the disk somewhat similar to that shown in Fig. 3, but the stressing of the disk under the constrictive reaction of the rim is effected by means of a shim member 36 having a wedge portion 37 forced between the felly member and the rim by means of the bolts 38.

In Fig. 5 the laterally deflected peripheral portion of the disk underlies the felly member 39 by means of which it is held under permanent stress, the rim 19 being assembled therewith by means of the shim 40 and the bolts 41.

Fig. 6 represents a construction in which the peripheral portion 20 of the disk is laterally disposed at a slight incline to the horizontal and the stressing of the disk is accomplished by the wedging action of the rim surface 42 under the force applied to the rim flange 43 by the bolts 44.

According to Fig. 7, the two independent sheets forming the disk, whether of steel or other material, present inclined steps 20°, 95 20° and 20° upon which inclined portions of the rim are respectively forced by means of the shim 45 under the pressure of the bolts 46. These bolts 46 at the same time tend to force together the locally separated sheets whereby more intimate contact is obtained inwardly and outwardly of the bolts and the stressing effect assisted.

It will be noted that the holes in the disks about the several bolts are larger than is strictly necessary to receive the bolts. This permits the accommodation of bolt to disk as the latter shifts slightly under the stressing action when the bolts are tightened.

While in each of the figures I have shown an assembly of the disk with the hub and peripheral portions of the wheel which places and maintains the disk under stress, it will be understood that for some purposes this supplemental strengthening of the disks would not be required and the invention is not to be considered as necessarily an association of the two ideas of disk construction and wheel assembly as the one has elements of decided value independent of the other.

I claim:

1. In a wheel, the combination with the hub portion and the tire-carrying peripheral portion, of an intermediate disk portion comprising sheet material have a coefficient of elasticity substantially lower than steel, the said disk assembled with the hub and peripheral portions of the wheel and maintained under radially re-acting stress.

2. In a wheel, the combination with the hub portion and the tire-carrying peripheral portion, of an intermediate disk portion comprising a sheet of non-metallic material radially yieldable and maintained under radially acting stress in assembled relation with the other portions of the wheel.
3. In a wheel, the combination with the hub portion and the tire-carrying peripheral portion, of an intermediate disk portion comprising a plurality of sheets of material having a co-efficient of elasticity substantially lower than steel, the wheel radius having an ogee curvature substantially throughout the disk area.
4. In a wheel, the combination with a hub portion and the tire-carrying peripheral portion, of an intermediate dished disk portion comprising a plurality of reversely curved sheets of fibrous material arranged in contact substantially throughout the disk area.
5. In a wheel, the combination of the hub portion and the tire-carrying peripheral portion, of an intermediate disk portion presenting a series of concentric convex and concave zones and comprising a plurality of sheets, including sheets of wood arranged with the grain in intersecting relation.
6. In a wheel, the combination with the hub portion and the tire-carrying peripheral portion, of an intermediate disk portion comprising a plurality of sheets, including sheets of organic fibrous material, the component disk-sheets disposed in contact substantially throughout the disk area, said disk yieldable radially and assembled with the hub and rim portions of the wheel under radially re-acting stress.
7. A dished wooden disk wheel having an annular reversely curved zone between its center and rim.
8. A dished wooden disk wheel formed of a plurality of layers of wood and having an annular reversely curved zone between its center and rim.
9. A dished wooden disk wheel having a flat central portion and an annular reversely curved zone between its flat central portion and rim.
10. A disk body for wheels formed of non-metallic material reversely curved to provide a forwardly concave zone adjacent the hub portion and a forwardly convex zone adjacent the periphery.
11. A disk body for wheels formed of non-metallic material reversely curved to provide a forwardly concave zone adjacent the hub portion and a forwardly convex zone adjacent the periphery, the disk crossing the plane of impact of the wheel intermediate its center and periphery.
12. A wheel comprising a disk body formed of non-metallic material and having a forwardly concave zone intermediate its center and periphery, in combination with a metal rim forming a constrictive member about the periphery of the wheel body.

In testimony whereof I have hereunto signed my name.

GEORGE H. FORSYTH.
